LOOM APPARATUS

Maurice S. Rosen, New York, N. Y., assignor to
Anne Walters, New York, N. Y.

Application October 16, 1939, Serial No. 299,591

10 Claims. (Cl. 28—15)

This invention relates to weaving looms for the fabrication of rag rugs and the like, and particularly to devices in this category adapted to employ strips of silk or other fabric tied along supporting cords or strands to form braids of rug material that are subsequently coiled and stitched together to produce the finished rug.

In the process of weaving by looms of this class, it is of utmost importance that the braiding strands be maintained at a constant tension so as to facilitate the weaving operation and enable the production of a uniform product. It has been found, however, that there is a loosening up of the strands in certain commercial devices, due generally to inefficient tensioning means and insecure supports for the strand holding elements. It is primarily within the contemplation of this invention to eliminate this disadvantage by providing, in a simple and inexpensive device, firm and secure strand-tensioning means, and permitting the required tension to be maintained throughout the weaving operation. This I accomplish, in a preferred form of my invention, by employing strand supporting uprights with intersecting slots adapted to frictionally receive two contiguous portions of two parallel braiding strands, thereby providing a double-acting friction grip capable of holding the strands taut until released, as will more clearly hereinafter appear.

Certain devices of this class are of wire construction, requiring spot-welding operations in their manufacture, and are costly, bulky and inconvenient to handle. It is also an object of my invention to improve over such devices by providing an easily fabricated, inexpensive and conveniently handled apparatus that can be readily assembled and disassembled.

It is also within the contemplation of this invention to provide a compact and self-contained unit, whereby the bales of twine, strips of textile material, loom elements and supports therefor are all conveniently contained in a unitary kit which also forms part of the apparatus. And in this aspect of my invention, it is an additional object to further employ the kit not only to retain the bales of twine in proximate relation to the loom elements, but also to provide a firm support for the strand supporting members. With this arrangement no separate bale supporting spindles need be employed to keep the bales from rolling to the floor, nor is there any necessity of providing separate storage cartons for the loom members, the bales of twine, and the strips of textile material.

Other objects, features and advantages will appear from the drawing and the description hereinafter given.

Referring to the drawing:

Figure 1 is a perspective view of my invention including the kit, weaving and loom elements disassembled within the kit, and the partly opened cover.

Figure 2 is a perspective of the loom apparatus of Figure 1 shown in its assembled condition.

Figure 3 is an enlarged fragmentary perspective of the two uprights illustrated in Figure 2 with the braiding strands and knotted textile strips in place during the process of weaving.

Figure 4 is a plan view of a portion of the braiding strands and a strip of textile material loosely entwined thereabout during one step of the weaving process.

Figure 5 is a view substantially similar to that of Figure 4 with the knot in the strip drawn during the process of sliding it along the braiding strands.

Figure 6 is a diagrammatic plan view of a portion of the box of Figure 2 showing one arrangement of the uprights.

Figure 7 is a view substantially similar to that of Figure 6, showing a modified arrangement of the uprights, and

Figure 8 is a diagrammatic plan view of the box of my invention showing still another arrangement of uprights.

In the drawing, the entire apparatus constituting my invention comprises the self-contained unit 10 including the box or kit 11 with the four lateral walls 12, 13, 14 and 15, these walls serving not only as box sides for retaining in place the weaving material and the loom elements when disassembled, but also as supports and retaining means for the strand-supporting uprights and weaving materials during the weaving operation, all as will more fully hereinafter appear. In the form of my invention disclosed in the drawing, the said strand-supporting uprights are the two members 16 and 17 adapted to operatively receive and hold therebetween the substantially parallel adjacent braiding strands 18 and 19 extending from the two bales of twine 20 and 21, respectively, which are positioned within the box 11. Also contained within the box 11 are the previously cut strips of fabric 22 which are used in the fabrication of the braids of rug material, as will hereinafter be described. In the preferred set-up of this apparatus, the box 11 is placed within the cover 23 as illustrated in Figure 2, thereby not only conveniently disposing of said cover, but

also providing reinforcement to the lateral sides of the box 11 for supporting the uprights 16 and 17. It is understood, however, that the said uprights can be suitably supported on the lateral walls of the box 11 without employing the cover 23, should such an arrangement be deemed preferable or desirable.

The said uprights 16 and 17, according to the preferred form illustrated, have bifurcated lower portions produced by the longitudinal slots 24 and 25 in said uprights. The upper portion of at least one of the uprights 16, as clearly shown in Figure 3, contains an arrangement of two intersecting slots 26 and 27, the other upright 17 being preferably provided with a hook 28 as illustrated. The said slots 26 and 27 cooperate with the hook 28 to constitute strand-holding means whereby the said braiding strands 18 and 19 are maintained in tension throughout the weaving operation. Although the specific arrangement illustrated shows one upright with a cross-slotted upper portion and the other with a hook, this invention is not to be limited to this particular arrangement inasmuch as both uprights may have cross-slotted upper portions within the contemplation of this invention.

In setting up the apparatus constituting this invention, the said uprights 16 and 17 are supportably positioned over opposite walls 12 and 13 of the kit, the bifurcated lower portions straddling the walls 12 and 13 and the adjacent walls of the cover 23, whereby the supports are frictionally maintained firmly in place. It is preferred in this arrangement that the uprights 16 and 17 be placed adjacent a connecting wall of the box such as 14, thereby providing a further support therefor. The ends of the two strands 18 and 19 are then tied together at 29, and such joined portion placed over hook 28 as shown in Figure 2. The two adjacent strands are then drawn taut and extended through slot 26 (see Figure 3), around a portion of the upright 16, and then through cross-slot 27, the emerging portions 30 of the two strands being preferably drawn in a generally downward direction to bring the two intersecting portions of the strands within the slots into actual engagement. It is thus obvious that by such an arrangement the two braiding strands 18 and 19 can readily be assembled upon the uprights 16 and 17 and drawn to the desired tension; and due to the frictional engagement of the walls of slots 26 and 27 with said strands, and to the actual cross-engagement of said strands with each other within the slots, such tension will be maintained throughout the braid-forming operation. It is of extreme importance in an apparatus of this nature that intermediate portions of the braiding strands such as those which are supported by the upright 16 be releasably retained in place preferably by suitable friction means, inasmuch as such portions must be repeatedly disengaged from upright 16 when successive sections of the braids are completed.

When the strands are in position for braiding, as indicated in either Figure 2 or 3, a strip 22 is stretched across the strands after they are slightly separated, and the ends pulled up from underneath between the strands, as clearly indicated in Figure 4. The ends of the strip are then grasped and drawn in the direction of the arrow, the knot automatically tightening itself during this process, as shown in Figure 5. When the fully formed and knotted strip 22 finally reaches previously formed knots 22a, the cycle of operation is repeated with another strip, and so on.

It will be noted that after a knotted strip is completed and pulled to its final position, there will be a slight space 31 formed between the strands adjacent the knotted strip, thereby facilitating the separation of the strands to the position shown in Figure 4. There is hence no necessity of providing any space-consuming structure for positioning the strands in divergent relation, as has been found necessary in certain other commercial devices.

Although it is preferred, as aforesaid, to employ two substantially parallel braiding strands, the uprights forming part of this invention are also adapted to operatively support a single braiding strand, over which any other known form of loop or knot can be formed from the strips 22.

After sections of the strands between the uprights are completed, such braided sections are detached from the hook 28 and slots 26 and 27 of the uprights, and the next succeeding portion of the strands positioned in place,—the said hook 28 being inserted between two adjacent strands in a completed portion of the braid, as indicated in Figure 3. Following these operations, the braids are trimmed, coiled and stitched or otherwise fastened together to form a completed rug, mat or other similar article, in conventional manner.

In order to provide a more secure support for the uprights such as 16 and 17, the lower portions thereof may be provided with angular slots 32 whereby the said uprights could be positioned at the corners of the box 11, as indicated in Figure 7. By means of this arrangement, each upright is operatively supported by two adjacent walls, and is held against lateral movement.

Figure 8 shows another modified form of my invention employing uprights 16 and 17 with angular slots 32 in the lower portions thereof similar to that illustrated in Figure 7, the uprights however being disposed at diagonal corners of the box thereby providing not only a sturdy structure, but also longer sections of braiding strands.

In the various forms above described, it will be observed that the lateral walls of the box 11 serve not only the purpose of supporting the uprights 16 and 17, but also the function of retaining means particularly for the bales of twine 23 and 21. In this manner such bales are kept in close proximity to the loom elements, and are also prevented from rolling to the floor. Obviously the use of the box 11 as retaining means also for the strips 22 is a decided advantage.

To disassemble the apparatus all that need be done is to detach the uprights 16 and 17 from the supporting walls, and place them together with the weaving materials within the box. It is thus apparent that the entire unit not only serves as a compact kit for conveniently containing all the weaving elements and materials, but also as a structural element in the loom apparatus.

It is of course understood that the various embodiments above-described and shown in the drawing are illustrative of my invention and not employed by way of limitation, inasmuch as numerous changes and modifications may be made within the scope of the appended claims without departing from the spirit of this invention.

What I claim is:

1. An apparatus for forming a braid of rug material, comprising two spaced uprights with slotted lower portions, supporting walls extending into and in frictional engagement with said slotted portions for vertically supporting said uprights, two bales of twine, retaining means for

- said bales adjacent said uprights and cooperative-
ly associated with said walls, and strand holding
means on said uprights, two selected portions of
twine from said bales extending in parallel ad-
5 jacent relation between and being operatively held
by the said strand holding means whereby said
portions of twine form two adjacent braiding
strands substantially parallel throughout their
length.
- 10 2. An apparatus for forming a braid of rug ma-
terial, comprising two spaced uprights with
slotted lower portions, two bales of twine, a later-
ally enclosed box for said bales, certain of the
walls of said box extending into and in fric-
15 tional engagement with said slotted portions of
the uprights and vertically supporting the up-
right, and strand holding means on said up-
right, two selected portions of twine from said
bales extending in parallel adjacent relation be-
20 tween and being operatively held by the said
strand holding means whereby said portions of
twine form two adjacent braiding strands sub-
stantially parallel throughout their length.
3. An apparatus for forming a braid of rug
25 material according to claim 2, the two uprights
being positioned upon and operatively supported
by two opposite walls of the box.
4. An apparatus for forming a braid of rug ma-
terial according to claim 2, the two uprights be-
30 ing positioned upon and operatively supported
by two opposite walls of the box and in abut-
ment with the adjacent wall.
5. An apparatus for forming a braid of rug ma-
terial according to claim 2, the two uprights be-
35 ing positioned upon and operatively supported by
two diagonally opposed corner portions of the
box.
6. In an apparatus for forming a braid of rug
40 material from two strands of twine and strips
of textile material, two spaced uprights for sup-
porting therebetween said strands of twine,
strand holding means on said uprights for hold-
ing therebetween said strands of twine, said
45 holding means on at least one of said uprights
comprising two cross-slotted portions for receiv-
ing two contiguous portions of the strands ex-
tending from the other upright and frictionally
holding them in tension for operatively receiving
50 the said strips of textile material, and supporting
means for said uprights.
7. In an apparatus for forming a braid of rug
material from two strands of twine and strips of
textile material, two spaced uprights for sup-
porting therebetween said strands of twine,
strand holding means on said uprights for hold-
ing therebetween said two strands of twine in
substantially parallel relation, said holding means
comprising fixed anchoring means on one of said
uprights for adjacent portions of the strands, and
cross-slotted portions on the other upright for
frictionally holding contiguous portions of the
strands extending from said first-mentioned up-
right whereby the strands are maintained in ten-
sion for operatively receiving the said strips of
textile material, and supporting means for said
uprights.
8. An apparatus for forming a braid of rug
material according to claim 7, the upright with
the cross-slotted portions comprising a unitary
pole-like member with the upper terminal pro-
20 vided with two intersecting slots adapted to op-
eratively receive the said strands in crossing rela-
tion.
9. In an apparatus for forming a braid of rug
material from strands of twine and strips of tex-
25 tile material, two spaced pole-like uprights for
supporting therebetween said strands of twine, a
hook at the upper terminal of one of said up-
rights, the upper terminal of the other upright
containing two intersecting slots adapted to fric-
30 tionally receive therein in crossing relation
strands extending from said hook whereby the
strands are maintained in tension for operatively
receiving the said strips of textile material, the
lower portions of the said uprights being bi-
35 furcated, and supporting means for the uprights
in frictional engagement with the said bifurcated
portions thereof.
10. In an apparatus for forming a braid of rug
material from strands of twine and strips of tex-
40 tile material, a pole-like strand supporting up-
right with intersecting strand-receiving slots in
the upper portion thereof and a support-receiving
slot in the lower portion thereof, a support in en-
gagement with said last-mentioned slot, and
45 strand supporting means spaced from said up-
right and adapted to cooperate therewith for
supporting selected strands therebetween.

MAURICE S. ROSEN. 50
